2,634,405

TRAVELING BLOCK INDICATOR FOR OIL
WELL DERRICKS

Clifford E. Van Stone, Santa Maria, Frank J. Lopker, Los Angeles, and Burt Stanley Minor, Whittier, Calif.

Application March 29, 1949, Serial No. 84,196

2 Claims. (Cl. 340—282)

1

Our invention relates to a travelling block indicator for oil well derricks whereby a driller or operator may be visually appraised of the position of the travelling block within the derrick at all times.

An object of our invention is to provide a novel travelling block indicator in which a movable finger indicates the relative position of the travelling block in the derrick on a dial or chart in front of the driller or operator.

Another object of our invention is to provide a novel travelling block indicator in which the operator or driller is warned when the travelling block is at a dangerous elevation in the derrick so that the travelling blocks may be stopped before damage is done.

Another object of our invention is to provide a novel travelling block indicator in which the elevating mechanism of the blocks is automatically shut off when the travelling blocks reach a dangerous elevation in the derrick.

Still another object of our invention is to provide a novel travelling block indicator of the character stated in which any part of the indicating or controlling mechanism will "fail safe" that is, the driller will always be definitely appraised of any failure of any part of our mechanism.

A feature of our invention is to provide a novel travelling block indicator in which the indicating finger or arm is moved synchronously with the travelling block due to the fact that the mechanism is connected to the actuating mechanism of the travelling block, such as the crown block.

Another feature of our invention is to provide a novel travelling block indicator of the character stated, in which there is an electrical circuit and a pneumatic circuit, these being inter-connected, the pneumatic circuit operating the clutch and brake of the draw works.

Another feature of our invention is to provide a novel travelling block indicator of the character stated, in which there is an electrical circuit operating the indicator, an electrical, steam or diesel power unit operating the travelling block, the two being inter-connected so that either has certain selected control of the other.

Still another feature of our invention is to provide a novel travelling block indicator in which the electrical contacts within the instrument may be adjusted to provide for derricks of different height.

Still another feature of our invention is to provide a novel travelling block indicator which is compact in arrangement and may be readily

2

positioned on the floor of the derrick so as to be observable by the driller.

Other objects, advantages and features of invention may appear from the accompanying drawing, the subjoined detailed description and the appended claims.

In the drawing:

Figure 1 is a side elevation of an oil well derrick in which our invention is placed.

10 Figure 2 is a fragmentary front elevation of the instrument case.

Figure 3 is a fragmentary longitudinal sectional view of the instrument case.

15 Figure 4 is a fragmentary longitudinal sectional view of the instrument case taken at right angles to that shown in Figure 3.

Figure 5 is a sectional view taken on line 5—5 of Figure 4.

20 Figure 6 is a sectional view taken on line 6—6 of Figure 4.

Figure 7 is a fragmentary side view taken in direction of the arrows 7—7 of Figure 6.

Figure 8 is a sectional view taken on line 8—8 of Figure 4.

25 Figure 9 is a sectional view taken on line 9—9 of Figure 8.

Figure 10 is a fragmentary side view of one of the crown block sheaves and showing the selsyn generator mount.

30 Figure 11 is a diagrammatic view of the electrical system and the pneumatic system.

In the drilling of an oil well, a crown block is mounted on the top of the derrick and a travelling block with a hook, elevator links and elevator attached thereto is suspended from the crown block on cables and moves within the derrick for the purpose of vertically moving pipe and drilling equipment in the derrick. Due to accident or carelessness, the travelling block is occasionally permitted to move too high in the derrick, thus striking the crown block and causing serious damage and possible serious injury to the workmen.

45 The derrick 1 is of usual and well known construction, and similarly the crown block 2 is usual and well known in the art. The travelling block 3 is suspended from the crown block 2 in the usual manner and a cable 4 is trained over the sheaves in the crown block which vary in number in use according to the load to be hoisted and one or more of these sheaves 5 move synchronously with the block 3, that is, the rotation of the sheaves 5 will always be the same relative to the movement of the block 3 in the derrick.

50 55 The indicating mechanism, to be described subse-

quently, will be connected to one of the least number of sheaves 5 normally used and will be further described.

The draw works 6 is usual and well known and this draw works is operated by the driller to control the movement of the block 3. The draw works include a brake and a clutch, all of which is usual and well known and will be understood by those trained in the art.

In order that the driller may have a visual indication of the position of the travelling block 3 immediately before him, we provide a selsyn-generator 7, which is mounted on or at the crown block 2, and is suitably connected to one of the above mentioned sheaves 5, preferably by means of the chain drive 8. A selsyn motor or receiver 9 is connected to the generator 7 by means of the wires 10, which run vertically in the derrick 1 from the top to the bottom thereof. It will thus be evident that any movement of the selsyn generator 7 will be immediately transmitted to the selsyn motor 9 and the movement of the rotors of these two selsyns will be synchronous and will be identical. It is to be noted that the windings on the rotors of the instruments 7 and 9 are electrically connected as are also the field windings.

Thus, as the sheave 5 rotates with the vertical movement of the travelling block 3, the selsyn instrument 7 will rotate correspondingly at the same time the selsyn receiver 9 will rotate and the shaft 11 is suitably geared to a shaft 12 journalled in the housing 13 of the floor instrument. The shaft 12 is journalled in a bracket 14 secured within the housing and a second shaft 15 is journalled in the bracket 16, adjacent the upper end of the housing 13. A sprocket 17 is mounted on the shaft 12 and a similar sprocket 18 is mounted on the shaft 15. A chain 19 encircles these two sprockets and this chain is moved synchronously with the selsyn 9 and, therefore, is synchronized with the movement of the travelling block 3. A rider 20 is fixedly secured to the chain 19 and moves vertically within the housing 13, but only on one reach of the chain 19, that is, the rider 20 never passes over the sprockets 17 or 18. Thus, the height of the derrick is simulated by the movement of the rider 20 on one reach of the chain 19 and from the lower sprocket 17 to the upper sprocket 18. A knob 21 extends from the sprocket 17 and it is possible to manually rotate the sprocket 17 and the chain 19 as well as the rider 20 to synchronize this rider with the position of the travelling block 3 in the derrick.

To insure that the rider 20 will accurately move in its vertical path, we provide a pair of channel guide strips 22 and 23, in which the rider 20 moves. The rider is provided with spaced rollers 24 which fit in these channel guides, thus insuring the proper and accurate movement of the rider. The guides 22 and 23 are fixedly secured to brackets 25 and 26 which are fixedly secured to the wall of the housing 13. Strips 27 and 28 extend between the brackets 25 and 26 acting as stiffeners for the guides 22 and 23, and also as mounts for the contact strips, which will be subsequently described.

The housing 13 has a front panel 29 which may be calibrated in feet to indicate the height of a derrick, or it may have a picture of a derrick thereon to simulate the type of derrick in which the apparatus is used. A plate 30 at the top of the panel 29 with the wording "Crown" may be adjusted in the slots 31, so that various heights of derricks may be indicated. A plurality

of tabs 32 are mounted on the face of the panel 29 and these tabs indicate the actual position of the derrick finger with relation with the elevator, the top safe limit for the block 3, and other indications which may be desired. These tabs are also adjustable in a slot 33 to provide for various heights of a derrick.

The rider 20 has a finger 34 secured thereto and this finger moves in a slot 35 in the panel 29. The length of the finger representing the combined length travelling block 3, the hook, the elevator links, and the elevator. The top end of the finger 34 indicates the position of the block 3 in the derrick and shows the driller where this block is at all times. The lower end of the finger 34, likewise, indicates the position of the elevator.

Thus far we have described the visual method of indicating the positioning of the travelling block 3 in a derrick. In addition to this visual indication, we also provide an electrical circuit which will actuate audible signals and visual signals, and also through a pneumatic system controlled by the electrical system will automatically stop the draw works 6 in the event that the travelling block 3 reaches a dangerous height in the derrick.

The rider 20, in its vertical movement, engages electrical contacts which consist of a bus bar 36 and adjustable contacts 37-38-39. The contacts 37-38 are adjustable relative to each other and also on the plate 28 so that adjustment may be made for different heights of derricks. These contacts are adjusted by loosening the plates 40. Similarly, the contact 39 is adjusted by loosening the plates 41.

Our device is so designed and arranged that if failure occurs within the device or to either the electrical or pneumatic supply, the device will "fail safe" and prevention is also made (within the limits of human error) so that the device cannot be put into operation until the air supply and the electrical supply have been proved out. Within the electrical circuit we provide a magnetically operated contactor switch 42, which is normally open. This switch is closed by the push button 43, which energizes the coils of the switch 42 and causes this switch to close. When the switch 42 is closed, the holding circuit is established. This holding circuit leads from one incoming electrical lead 44, through the coil 45 of the switch, then through the pressure switch 46 in the air or pneumatic circuit, which will be subsequently described. The circuit then extends through the two limit switches 47-48, which prevent over travel of the indicator pointer 34, and thence back to the other incoming electrical lead 49. The switch 42 will be opened and all power removed from the equipment when the push button 50 is open or by failure of the air supply. Also, the switch 42 will be opened on openings of the air pressure switch 46 or the opening of either of the limit switches 47 or 48. The power from the main switch 42 goes to an overload relay 51 which is magnetically operated when the main contact 42 is closed. In case this overload relay 51 is caused to open by a short circuit or other overload on the electrical circuit, it can be reset after removal of the overload by pressing the reset push button. The power from the overload relay 51 is then taken directly to the field of the selsyn 7 through the wires 10, and also to the field of the selsyn 9 through this same wire. The main power is also taken from the overload relay 51

through the wires 52—53 to lights 54—55—56. Current is thus supplied to bus bar 36 and contacts 37—38—39.

The light 54, which is preferably white, is connected between the two leads from the overload relay 51. This light is the "power on" light and indicates that the device is in operation. A warning horn 57 is provided to warn the operator that he is approaching a danger limit. This horn is energized through a timer 58, which is provided to limit the length of time during which the horn will sound. The horn will sound for one or two seconds each time the travelling block 3 reaches a set height. The timer 58 is an instantaneous reset type which is energized when the rider 20 engages the contact 39, as will be evident from the drawing. When the rider 20 closes the circuit between the bus bar 36 and the contact 38, a yellow light 55 will be lit, thus indicating that the travelling block is at a pre-determined position, usually the finger height in the derrick. When the rider 20 closes the circuit between the bus bar 36 and the contact 37, the red light 56 will be lit and at the same time will energize the relay 59, thus opening this relay. The relay 59 is in series with the solenoid of the three-way operated air valve 60. The opening of the relay 59 will de-energize the solenoid 60 and thus operating the valve in the air system, which will be subsequently described, will release the clutch on the draw works, and at the same time will apply the brake on the draw works bringing it to a stop.

Considering now the air or pneumatic circuit, which operates the usual clutch and brake of the draw works 6. This air circuit consists of a check valve 61 in the line from the usual well known master four-way valve 62. The air then extends to the brake cylinder. An air relay valve 63 is piped to the master valve 62 and directs the air to the clutch. The elements 61 and 63 are operated by application of air pressure from our safety device. When the draw works is in use, air is applied from the master valve 62 to the clutch and the line between these two elements is under pressure. As the same time, air is exhausted from the cylinder through the four-way valve 62 to atmosphere.

The operation of the safety device is as follows:

Air is applied to the relay valve 63 which closes the air line from the valve 62 and opens the air line from the clutch. This exhausts the air from the clutch to atmosphere and releases the clutch. At the same time, air is applied through the check valve 61 directly to the cylinder, thus setting this brake and stopping the draw works. Air pressure to the relay valve 63 and the check valve 61 is applied through a three-way solenoid operated valve 64. This is the valve which is controlled by the solenoid 60, previously described. This valve 64 is so wired that air pressure will be applied to the control circuit whenever the solenoid 60 is de-energized. This feature is included to make the device "fail safe" in case of failure of the electrical power. When the solenoid 60 is energized the air circuit from the relay valve 63 and the check valve 61 is open to atmosphere allowing normal operation of the draw works.

An electrical pressure switch 65 is installed in the air line 66 to the solenoid valve 64. This pressure switch has electrical contacts which are normally opened when there is no air pressure. When air pressure is applied the contacts 46 are

closed. This switch is included in the circuit to make the equipment "fail safe" as the switch is connected in series with the electrical wiring. Thus, failure to properly supply air pressure to the safety device will cause the electrical contacts 46 to remain open and this in turn will prevent the main electrical contactor 42 to remain closed. Thus, the device cannot be put into operation unless air pressure is first proved out.

An auxiliary bleeder valve 67 is installed in the pipe 66 so that air pressure in the line to the relay valve 63 and the check valve 61 can be bled to atmosphere. Thus, the operation of the draw works can be continued after a shut down caused by electrical power failure. Should the operator wish to operate the equipment above the limit point 37 and while the relay 59 is open, he can re-energize the relay by closing the bypass push button 68, thus releasing the brake and reengaging the clutch. The push button 68 is spring loaded and will remain closed only as long as it is manually held. Release of the push button will cause the three-way air valve 64 or the coil 60 to become de-energized as long as the relay 59 is open.

From the foregoing description, it will thus be evident that our indicator will not only furnish a visual indication of the relay position of the travelling block 3 within the derrick, but it will also operate supplementary lights, horn and the like, and will even entirely shut down the draw works at pre-determined points.

Operation

With the travelling block 3 in its lowest position, the indicator or rider 20 is synchronized by adjusting or turning the knob 21. The contacts 42 are now closed which lights the "power on" lamp 54. When the elevator suspended from the travelling block reaches the finger in the derrick, the yellow light 51 will go on. At this time the rider 20 is engaging the contact 38. When the top of the travelling block reaches the warning point the light 55 goes out and the red light 56 goes on. The horn 57 has also been sounding during the time that the yellow and red lights are one. When the red light 56 is lit, the limit switch 48 will also be operated, thus actuating the pressure switch 65 and actuating the valve 64 to release the clutch and set the brake. As the travelling block is lowered, the red and yellow lights will be successively extinguished and if the rider 20 moves to a bottom position, the bottom limit switch 47 will be engaged, which again will operate the pneumatic circuit to release the clutch and set the brake of the draw works.

Having described our invention, we claim:

1. In combination with a derrick, a travelling block in the derrick mounted for vertical movement therein, means connected to the travelling block to actuate the same, a travelling block indicator comprising an instrument housing mounted on the floor of the derrick, a rider mounted for vertical movement in said housing, said rider having a length proportionate to the travelling block, visual elevation indicating means on said housing, said rider moving adjacent the visual elevation indicating means, electrical drive means connected to said rider to move said rider synchronously with the block, a second electrical means operable by the block and connected thereto, said second electrical means being electrically connected to the said electrical drive means, a scale on said housing 70 over which said rider moves to indicate the posi-

tion of the travelling block, said scale being in the same proportion to the total movement of the rider as the height of the derrick is to the total movement of the block, and means actuated by positioning of the upper and lower extremities of said rider, said last named means extending to and controlling the travelling block actuating means.

2. In combination with a derrick, a travelling block in the derrick mounted for vertical movement therein, means connected to the travelling block to actuate the same, a travelling block indicator comprising an instrument housing mounted on the floor of the derrick, a rider mounted for vertical movement in said housing, said rider having a length proportionate to the travelling block, visual elevation indicating means on said housing, said rider moving adjacent the visual elevation indicating means, electrical drive means connected to said rider to move 20 said rider synchronously with the block, a second electrical means operable by the block and connected thereto, said second electrical means being electrically connected to the said electrical drive means, a scale on said housing over which said rider moves to indicate the position of the travelling block, said scale being in the same proportion to the total movement of the rider as the

height of the derrick is to the total movement of the block, the position of the rider on the scale being proportionately identical to the position of the block in the derrick, and means actuated by positioning of the upper and lower extremities of said rider, said last named means extending to and controlling the travelling block actuating means.
